VACUUM CLEANING MACHINE

Hermon C. Keen, Brazil, Ind., assignor to Continental Car-Na-Var Corporation, Brazil, Ind., a corporation of Indiana

Application September 27, 1951, Serial No. 248,479

6 Claims. (Cl. 183—35)

1

This invention relates to a vacuum cleaner of the type which is particularly well adapted for industrial uses. It embodies an electric motor operating a multi-stage turbine fan for creating vacuum on the one hand and pressure on the other hand. The motor is removably mounted on a cover which is detachably retained on a tank adapted to receive dirt, or liquids, as the case may be, with an enclosed filtering medium across the tank, all embodied in a portable machine.

A primary object of the invention is to provide in one unit a machine which will have sufficient vacuum capacity for cleaning ordinary dust and discharging it into the tank and there retaining it; picking up metal, such as chips and particles around metal cutting machines, and other articulate matter. Also the machine has the advantage of picking up water or other liquids to bring those liquids into the tank and there retain them. Furthermore, the unit is also adaptable for spraying and for emptying the tank contents under pressure.

These and many other objects and advantages of the invention will become apparent to those versed in the art in the following description of one particular form as illustrated in the accompanying drawings, in which

Fig. 1 is a view in side elevation and partial section of the structure embodying the invention;

Fig. 2 is a view in top plan;

Fig. 3 is a view in top plan of the machine with the motor supporting cover removed;

Fig. 4 is a view in central vertical section on the line 4—4 in Fig. 2;

Fig. 5 is a view in transverse section on the line 5—5 in Fig. 1;

Fig. 6 is a view in side elevation and section of a modified form of the invention;

Fig. 7 is a detail in elevation from the inside of the tank of a liquid level control in the form as shown in Fig. 6; and

Fig. 8 is a wiring diagram of the circuits employed in the form of the invention as illustrated in Fig. 6.

In one particular form of the invention, there is provided a cylindrical tank 10 to have a capacity of one and three-quarters bushels or ten gallons approximately. The tank 10 is preferably mounted upon a plurality of casters 11, herein shown as three in number.

The filter bag 12 is formed to fit loosely within the upper end portion of the tank 10, and rest on its top edge by means of an outturned heavy

2

rubber flange 13. The bag 12 is made out of a fabric which will permit the passage of air therethrough but at the same time will filter out fine dust. Within the filter bag 12 there is a skeletonized metal frame generally designated by the numeral 14. This frame has an upper and lower hoop 15 and 16 respectively surrounding staves 17, six in number, each stave 17 being an upturned end of a crossbar 18. These bars 18 are bowed upwardly from the lower ends of the staves 17 and cross each other at a central point where they are secured by any suitable means, herein shown as by a rivet 19. The staves and bars 14 are provided to prevent the collapsing of the bag 12 upwardly as air is pulled upwardly therethrough, the bag 12 having its underside drawn up and supported against further upward travel by means of coming into contact with those bars 14.

20 The flange 13 also serves as a gasket between the top rim 20 of the tank 10 and the underside of a top cover 21. This cover 21 is secured snugly in position, compressively against the flange 13 by means of a number of bolts 22, herein shown as three in number, each rockably carried by the tank 10 and having a thumb screw 23 screw-threadedly engaging thereon to turn down against a pair of ears 24 and 25 in each instance, the bolt 22 entering between the ears.

25 The cover 21 has a circular opening 26 therethrough, and a heavy section piece of rubber 27, herein indicated as being sponge rubber, is secured to the cover 21 around the margin of the opening 26. On this rubber 27 there is rested the motor-fan unit 28 and held downwardly thereagainst by means of the two straps 29 and 30, Fig. 2, which are secured hingedly by ends to the cover 21 and which have thumb screws 31 engaging the opposite ends, Fig. 2.

30 The cover 21 has a pressure discharge end nozzle 32 on the one end, and an intake nozzle 33 on the other end, over which nozzle 33 a hose 34 is telescoped. The other end of the hose 34 is connected through a fitting 35 with the cover 21 to provide a passageway 36 from the inside of the cover 21 into the hose 34. In this connection of the hose, there is a vacuum tended to be set up in the tank 10 upon the operation of the motor unit 28.

35 On the side of the tank 10, there is a fitting 37 provided to which a hose (not shown) may be attached to in turn be connected to a wand or to any nozzle or tool which is intended to be employed in the cleaning or blowing operation. This fitting 37 opens into the tank 10, and

carries on the inside thereof a tube 38 which is turned downwardly to terminate by a lower end 39 in spaced relation but close to the floor 40 of the tank 10.

A short tube 41 is mounted to be carried horizontally inside of the tank 10 from an opening 42 therethrough at approximately the same level as that of the fitting 37. This tube 41 carries a butterfly valve 43 therein toward its inner end, and this valve 43 is mounted on a shaft 44 which extends diametrically through the tube 41 and carries on an outer end thereof a float rod 45 in fixed connection therewith. On the outer lower end of the rod 45 there is a float 46, normally hanging downwardly as indicated in Figs. 4 and 5, and in which position the valve 43 is closed as is indicated in Fig. 4. Across the inner end of the tube 41, there is a flapper valve 47 normally closing off the tube under the influence of gravity, but being free to be shifted to the dashline position as in Fig. 4 should there be pressure on the outside of the tank 10 greater than on the inside.

In the modified form of the invention as illustrated in the Figs. 6-8, the tank 10 is provided with a pipe generally designated by the numeral 50 which connects with the fitting 37 to have a length 51 extend horizontally within the tank, and from which horizontal length there is a downturned length 52 carried downwardly to terminate by an end 53 in spaced relation from the floor 40 of the tank 10. The horizontal length 51 extends beyond the connection of the downturned length 52 to terminate by the end portion 54. On the end of this portion 54, there is a flapper valve 55 normally dropping to a closed position under the influence of gravity.

A float 56 is mounted inside the tank 10 at any desired level therein to control the upper limit or level of fluid in the tank 10 before the device is to be automatically shut off. In the form herein shown, the float 56 is mounted at a relatively low position for the sake of clarity in illustrating the invention. The float 56 in this particular form is mounted to slide vertically through a bracket 57 to have an upper end of the float stem 58 in the path of a lever 59 which in turn is in the path of a switch 60 so that when the float 56 reaches a predetermined elevation, the switch 60 will be opened, the switch 60 being normally closed. From the switch 60, a cable 61 leads to a connecting outlet 62. A cord 63 leading from the motor unit 28 carries a male plug 64 which is detachably engaged with the outlet 62 so that it may be detached when the cover 21 is to be removed from the tank 10, or the motor 28 is to be lifted and carried about and a longer cord is inserted between the male plug 64 and the outlet 62. The current supply cord 65 also connects with the outlet 62. A general outline of the circuit is illustrated in Fig. 8.

Operation

In operating the form of the invention as illustrated in Figs. 1-5 inclusive, the hose (not shown) is attached to the fitting 37 with the desired tool connected thereon. The motor 28 is set into operation by manipulating the switch 66, with the hose 34 connected as has been described and as is illustrated in the drawings. With the operation of the motor 28, the tank 10 is tended to be evacuated, air being drawn in through the fitting 37 and through the pipe 38. As long as the machine is being used as a vacuum cleaner on dry materials and is not being

used to pick up liquids, this will be the entrance of the air into the tank 10. The air will travel from within the tank 10 upwardly through the filter bag 12, and out through the hose 34 and through the unit 28 to discharge through the nozzle 32. When it is desired to clean the bag 12, the hose 34 is disconnected from the motor unit nozzle 33 and connected on the other nozzle 32 so that pressure is then created within the tank 10, the air being forced in a reversed manner through the bag 12 tending to clean the dirt off of its under and outer surfaces to deposit it in the tank 10 and from which the dirt will be blown upwardly through the discharge pipe 38 and out through the fitting 37, also through the connected hose as the case may be. When the machine is to be employed to pick up water, such as after scrubbing a floor, or even when there have been leaks and the water is spread pretty well over the floor and the like, the machine is still operated as a vacuum machine with the hose 34 connected on the nozzle 33 so that the inside of the tank 10 is tended to be evacuated, and then the water and whatever air may be associated therewith is pulled in through the fitting 37 and down through the pipe 38. When the level of the liquid rises in the tank 10 sufficiently high, the float 46 will be lifted, and when it is lifted, the valve 43 will be opened, and air will then come through the tube 41 lifting the flapper valve 47 so as to prevent further bringing in of water. The air will flow through the tube 41 in this manner rather than being carried down against the water present in the tank 10. In other words, the machine automatically quits lifting the water into the tank 10 when the tank 10 becomes sufficiently filled as to reach that point beyond which further water is not desired, or for the purpose of preventing the water or any splashing thereof from getting onto the filter bag 12. This prevents moisture from being taken through the motor unit 28.

When the water is to be evacuated from the tank 10, the hose 34 is again switched from the nozzle 33 to the nozzle 32 whereupon the tank 10 is internally pressurized and the valve 47 closes so that the water is forced up out through the pipe 38 to discharge through the fitting 37.

Referring now to the form of the invention as illustrated in Figs. 6-8, the overall operation remains substantially the same as that just described for the first form. In this second form the hose 34 is set up for evacuating the tank 10. The air will be pulled through the fitting 37 and enter the tank 10 primarily through the pipe 52, although the flapper valve 55 may open slightly to allow air to enter the tank 10 therefrom also. To evacuate the tank 10 the hose 34 is switched from the nozzle 33 to the nozzle 32 whereupon the flapper valve 55 will remain closed under the increased pressure within the tank 10, and the dirt will go out the pipe 52 and out through the fitting 37.

When this second form of the invention is used to pick up water, water will enter the fitting 37 and drop into the tank 10 through the pipe 52, until the float 56 is lifted whereupon the switch 60 is operated to interrupt the flow of current to the motor unit 28, and therefore the inside of the tank 10 then becomes equalized in pressure substantially with that of the atmosphere. Also as a further safety factor, when the level of the liquid within the tank 10 reaches a predetermined height, the flapper

valve 55 tends to open by reason of the differential of air flow, assuming that there is air mixed with the liquid as would be the case when the water is picked up from a scrubbed floor, so that the pressure within the tank 10 is tended to be increased to retard further water pickup.

While I have herein referred to the element 12 as a "bag," this element is not used in the ordinary sense that material will be entrapped therein. The material will be filtered from the air stream passing into the bag through its wall from below to leave the material or dirt on the outside thereof. Therefore, the element 12 is simply a filter diaphragm, the shape of which may obviously vary from a substantially planar circular disc to the decided centrally bagging thereof as illustrated in the drawings and as above described, depending upon the filtering area required, and the appended claims are to be read accordingly.

Therefore, while I have herein shown and described my invention in the best forms as now known to me, it is obvious that structural variations may be employed without departing from the spirit of the invention, and I therefore do not desire to be limited to those precise forms beyond the limitations which may be imposed by the following claims.

I claim:

1. In a vacuum cleaning machine, a tank having a floor and a side wall; a filter medium in the upper portion of the tank; an air pump carried by said tank; means selectively interconnecting the intake and the discharge of said pump for air flow through said filter respectively from and into said tank; a conduit leading downwardly by a length from an opening through the tank wall on the side of said filter removed from said pump intake and discharge flows to a lower end adjacent to but spaced above the tank floor; passageway means at a level in the tank above said conduit lower end opening to the exterior of the tank; a valve across said passageway means normally biased to a position closing said means, opening under a tank external pressure exceeding the tank internal pressure, and closing upon a tank internal pressure in excess of the external pressure providing a tank discharge passageway flow from said conduit lower end opening through the conduit and out said tank wall opening; and float operated means breaking the vacuum within said tank upon a predetermined degree of filling of the tank with liquid entering through said conduit.

2. In a vacuum cleaning machine, a tank having a floor and a side wall; a filter medium in the upper portion of the tank; an air pump carried by said tank; means selectively interconnecting the intake and the discharge of said pump for air flow through said filter respectively from and into said tank; a conduit leading downwardly by a length from an opening through the tank wall on the side of said filter removed from said pump intake and discharge flows to a lower end adjacent to but spaced above the tank floor; passageway means at a level in the tank above said conduit lower end opening to the exterior of the tank; a valve across said passageway means normally biased to a position closing said means, opening under a tank external pressure exceeding the tank internal pressure, and closing upon a tank internal pressure in excess of the external pressure providing a tank discharge passageway flow from said conduit lower end opening through

the conduit and out said tank wall opening and float operated means breaking the vacuum within said tank upon a predetermined degree of filling of the tank with liquid entering through said conduit; said filter medium being in bag form; and a skeleton frame within the bag to hold the medium against collapse during evacuation by said pump of said tank; said bag having freedom to shift from said frame upon pressurizing of the tank by said pump to aid in dirt accumulation removal from the medium for deposit in the tank and discharge from the tank through said conduit.

3. In a vacuum cleaning machine, a tank having a floor and a side wall; a filter medium in the upper portion of the tank; an air pump carried by said tank; means selectively interconnecting the intake and the discharge of said pump for air flow through said filter respectively from and into said tank; a conduit leading downwardly by a length from an opening through the tank wall on the side of said filter removed from said pump intake and discharge flows to a lower end adjacent to but spaced above the tank floor; passageway means at a level in the tank above said conduit lower end opening to the exterior of the tank; a valve across said passageway means normally biased to a position closing said means, opening under a tank external pressure exceeding the tank internal pressure, and closing upon a tank internal pressure in excess of the external pressure providing a tank discharge passageway flow from said conduit lower end opening through the conduit and out said tank wall opening and float operated means breaking the vacuum within said tank upon a predetermined degree of filling of the tank with liquid entering through said conduit; said passageway means comprising an upper portion of said conduit.

4. In a vacuum cleaning machine, a tank having a floor and a side wall; a filter medium in the upper portion of the tank; an air pump carried by said tank; means selectively interconnecting the intake and the discharge of said pump for air flow through said filter respectively from and into said tank; a conduit leading downwardly by a length from an opening through the tank wall on the side of said filter removed from said pump intake and discharge flows to a lower end adjacent to but spaced above the tank floor; passageway means at a level in the tank above said conduit lower end opening to the exterior of the tank; a valve across said passageway means normally biased to a position closing said means, opening under a tank external pressure exceeding the tank internal pressure, and closing upon a tank internal pressure in excess of the external pressure providing a tank discharge passageway flow from said conduit lower end opening through the conduit and out said tank wall opening and float operated means breaking the vacuum within said tank upon a predetermined degree of filling of the tank with liquid entering through said conduit; said passageway means comprising a separate conduit approximately at the level of the conduit opening through the tank wall.

5. In a vacuum cleaning machine, a tank having a floor and a side wall; a filter medium in the upper portion of the tank; an air pump carried by said tank; means selectively interconnecting the intake and the discharge of said pump for air flow through said filter respectively from and into said tank; a conduit leading downwardly by a length from an opening through the tank wall

on the side of said filter removed from said pump intake and discharge flows to a lower end adjacent to but spaced above the tank floor; passageway means at a level in the tank above said conduit lower end opening to the exterior of the tank; a valve across said passageway means normally biased to a position closing said means, opening under a tank external pressure exceeding the tank internal pressure, and closing upon a tank internal pressure in excess of the external pressure providing a tank discharge passageway flow from said conduit lower end opening through the conduit and out said tank wall opening and float operated means breaking the vacuum within said tank upon a predetermined degree of filling of the tank with liquid entering through said conduit; said passageway means comprising a separate conduit approximately at the level of the conduit opening through the tank wall; said vacuum breaker means consisting of a second valve across said separate conduit, and of a float interconnected to said second valve normally dropping under gravity influence to hold said second valve closed and opening the second valve upon being lifted by a rising liquid level in the tank.

6. In a vacuum cleaning machine, a tank having a floor and a side wall; a filter medium in the upper portion of the tank; an air pump carried by said tank; means selectively interconnecting the intake and the discharge of said pump for air flow through said filter respectively from and into said tank; a conduit leading downwardly by a length from an opening through the tank wall on the side of said filter removed from said

5 pump intake and discharge flows to a lower end adjacent to but spaced above the tank floor; passageway means at a level in the tank above said conduit lower end opening to the exterior of the tank; a valve across said passageway means normally biased to a position closing said means, opening under a tank external pressure exceeding the tank internal pressure, and closing upon a tank internal pressure in excess of the external 10 pressure providing a tank discharge passageway flow from said conduit lower end opening through the conduit and out said tank wall opening and float operated means breaking the vacuum within said tank upon a predetermined degree of filling 15 of the tank with liquid entering through said conduit; said passageway means comprising an upper portion of said conduit; a motor driving said pump; and said vacuum breaking means comprising a normally closed switch in electrical 20 circuit with said motor, and a float actuating said switch to an open circuit condition upon a predetermined liquid level height being reached in the tank.
